UNITED STATES PATENT OFFICE.

FRED E. SPARKS, OF BELLAIRE, OHIO.

SASH RETAINER AND FASTENER.

1,224,799.

Specification of Letters Patent.

Patented May 1, 1917.

Application filed April 14, 1916. Serial No. 91,107.

To all whom it may concern:

Be it known that I, FRED E. SPARKS, a citizen of the United States, residing at Bellaire, in the county of Belmont and State 5 of Ohio, have invented certain new and useful Improvements in Sash Retainers and Fasteners; and I do hereby declare the following to be a full, clear, and exact description of the invention, such as will enable others skilled in the art to which it 10 pertains to make and use the same.

This invention is a sash holder and lock designed more particularly for use with windows wherein the sashes are slidably 15 mounted in the frame.

It is a purpose of the invention to eliminate the employment of sash weights and cords by the utilization of resilient frictional devices carried by the sash to be placed in 20 engagement with the frame to retain the sash in a desired position relative to the frame. The frictional devices are preferably formed in pairs which are yieldable longitudinally, such frictional devices being 25 preferably in the form of roller bearings to permit of the slight longitudinal yielding found desirable in a device of this character. Where the frictional device consists merely of a spring actuated block positioned within 30 the sash to engage the frame transversely of the slidable movement of the sash, such device serves to deflect the sash from its normal sliding position into an inclined position, causing the frictional device to become 35 wedged between the sash and the frame.

This device overcomes the objections found in the resilient plunger type of sash fastener in providing spaced plungers having anti-frictional engaging surfaces, which devices 40 also serve as anti-rattlers for the sash.

The invention also includes a locking element which may be mounted for reciprocating movement between a plurality of the spaced resilient sash holding devices, the 45 lock operating to prevent movement of the sash when the foot of the lock is brought into frictional engagement with the window frame. The lock is also provided with means whereby its bolt cannot be retracted 50 except through manually controlled instrumentalities.

Other objects and advantages of the invention will be come apparent from the following detail description of the invention,

taken in connection with the accompanying 55 drawings and the appended claims.

While the preferred embodiment of the invention is disclosed in the accompanying drawings, it is to be understood that the construction therein set forth is for the purposes 60 of illustration only, and not as defining the limits of the invention.

In the drawings:—

Figure 1 is a side elevation disclosing the device applied to a window sash. 65

Fig. 2 is a front elevation of the assembled device.

Fig. 3 is a rear view of a cover-plate removed from the lock.

Fig. 4 is a view of the lock with the cover- 70 plate removed, parts being in section.

Fig. 5 is a detail view of the lock casing with one of the yieldable retaining plungers in position.

Fig. 6 is a bottom plan view of the locking bolt and its retaining element, showing the reverse position of the bolt to that disclosed in Fig. 4. 75

Fig. 7 is an end view of the locking bolt.

Fig. 8 is a top plan view of the locking 80 bolt and its retaining element.

Fig. 9 is a bottom plan view of the locking bolt and its retaining element.

Fig. 10 is a perspective view of the bolt retaining element. 85

Fig. 11 is a detail view of a key.

The casing indicated at 1 may be of any suitable material, such as metal, and may be formed in any preferred manner, as by casting. The casing is preferably provided with 90 wings 2, 3, whereby the casing may be secured to a window sash indicated at 4. The sash may be cut away to insert or inlay the casing 1, or the device may be applied in any other manner found desirable. The casing 95 1 is preferably provided with a removable cover indicated at 5, and this cover may be provided with a rotatable element 6 having a key-hole 7 therethrough, and which element 6 may be provided with an enlarged 100 portion 8 which is mounted to turn against the cover 5 in a suitable bearing formed in the cover. This member 8 may be in the form of a pinion and in the drawings is shown as a mutilated pinion. 105

The casing 1 is preferably provided with guide-ways 9, 10, which may be integral with the casing 1, said guide-ways 9, 10 being

spaced apart to provide a channel for the locking mechanism, and said guide-ways also forming an upper channel 11 and a lower channel 12 for the reception of the 5 resilient frictional elements. The member 9 may be provided with a rib 13 extending across the channel 11, and may be provided also with a recessed end portion 14. Into the channel 11 is shown positioned a block 10 15 having a chamber formed therein to receive a resilient element, such as a helical spring 16 which may be retained in the chamber and extend beyond the same into the recess 14 of the casing 1. The block 15 15 is preferably provided with a cut-out portion 17 on one face thereof providing a shoulder 18 at one end of said cut-out portion and the limiting stop 19 at the other end of the cutout portion. The cut-out portion 20 is adapted to receive the rib 13 of the member 9 to limit the reciprocating movement of the block 15 in the channel 11, by having the abutments 18 and 19 engage the rib 13. The end of the block 15 opposite 25 to that carrying the spring 16 is preferably provided with a roller 20 rotatably mounted upon a pin 21. The lower channel 12 may be provided with a block 22 similar to the block 15 of the upper channel 11, and this 30 block 22 may be cut away as at 23 to provide an elongated recess in which is positioned a rib 24 of the division section 10 of the casing, which limits the reciprocating movement of the block 22. Said block is 35 preferably provided also with a roller bearing surface 25 mounted similar to that described in connection with the block 15.

The blocks 15 and 22 are preferably at opposite ends of the casing 1 and the frictional engaging surfaces 20, 25 of the blocks coöperate to maintain the sash 4 in parallel relation to its frame, indicated at 26, when the sash is moved within the frame. Roller bearings 20, 25, also permit of easy slidable 40 movement of the sash 4 within its frame 26, when force is applied to the sash. The sash fastener and lock may be inserted in the frame 26 instead of the sash 4, as shown in the drawings, and as may be preferred. The 45 strength of the springs 16 of the device is sufficient to prevent the sliding movement of the sash relative to its frame when no external force is applied to the sash, thereby eliminating the necessity for the employment of counterbalancing mechanism.

Combined with the spaced frictional engaging devices to maintain the window in a predetermined position, is a locking element, which is preferably mounted between the 50 frictional engaging devices, and is designed to be manually moved to its locking position and provided with instrumentalities whereby the lock may not be released except by releasing a catch from engagement with 55 the locking bolt.

The locking element is shown in the form of a bolt 27, the engaging surface or foot 28 of which may be knurled, roughened or otherwise provided with an engaging face which will bite into the material of the sash 70 or frame and prevent movement of the sash relative to the frame. The bolt 27 is cut away as at 29 to provide a shoulder adjacent the engaging end of said bolt. The bolt is provided at this cut away portion with a rack 30 75 designed to coöperate with the pinion 8 carried by the plate 5, whereby when the pinion 8 is operated by a removable knob 31, the shank 32 of the knob coöperating with the key-hole 7 operates to rotate the pinion 8, 80 which engages the rack 30 and reciprocates the bolt 27 in the channel 33 of the casing 1. Rearward reciprocation of the bolt is limited by the end 34 abutting against the wall of the casing, while the forward movement 85 of the bolt 27 is limited by the leg 35 thereof engaging with a pintle 36 carried by the bolt retaining device, as will be clearly understood from an inspection of Fig. 4.

The channel 33 is provided with a recess 37, and is also provided with a substantially cylindrical plug 38 which is designed to serve as a rocker base for an arcuate end 39 of a lock retaining device 40. This lock retaining device is adapted to be fitted in a 90 cut-out portion of the bolt 27 and to be positioned between the bolt 27 and the back wall of the casing 1. This lock retaining element is provided with resilient means, shown in the form of a leaf spring 41 95 adapted to be seated in the recess 37 of the channel 33, the end 42 of the spring being deflected to engage a shoulder 43 of the recess 37, which causes the lock or bolt retaining device 40 to be pressed toward the 100 bolt 27.

That portion of the bolt 27 which is cut away and faces the bolt retaining device 40 is preferably provided with teeth 44, and the bolt retaining device 40 may be 110 provided with an extended flange 45 which is adapted to ride over the teeth 44 and successively engage a tooth as the bolt 27 is advanced by the rotation of the pinion 8 to prevent the retractive movement of the bolt 27, the resilient element 42 acting against the casing 1 to always maintain the flange 45 into engagement with the teeth 44. The end 39 of the bolt retaining device is provided for rocking movement against the 115 member 38, when said rocking movement is desired to move the bolt retaining device out of engagement with the bolt 27, as will be hereinafter explained.

The bolt retaining device is provided also 120 with an extension 46 adapted to be seated in a cut-out portion 47 of the rib 10 of the casing and this extension may be provided with the axial element 36 on one side and with another element of similar character 48 130

upon the opposite side of the extension 46, the element 48 being seated within an aperture 49 of the casing 1, while the element 36 is designed to be seated in the recess 50 formed in the pinion 8.

The device may be applied to either the sash or the frame, so that the bearing members 20, 25 are placed in frictional engagement to hold the sash in predetermined positions. The element for actuating the lock, such as a knob 31, is preferably removable from the device and may be in the form of a key as shown in Fig. 11, in lieu of the knob 31, for convenience in carrying the retracting element. When the lock has been advanced to its locking position, by the rotation of the pinion 8, by means of the knob 31 or the key, it is held in that position by the flange 45 engaging the teeth 44 of the lock, and the sash cannot be moved in any position. When it is desired to retract the bolt, the key 32 must be inserted through the key-hole 7 until the shank 32 of the key bears against the end of the element 36, and pressure must be applied to the key to depress the lock or bolt retaining device 40 by means of its element 36 to thereby release the flange 45 from engagement with the teeth 44 and while so pressing the key it should be rotated to cause the pinion 8 to engage the rack 30 to retract the bolt.

While various changes in the form and proportion of parts may be made, without departing from the spirit of the invention, the right is reserved to make such changes and alterations in the various details of construction herein set forth, as fairly fall within the scope of the appended claims.

Having thus described the invention, what is claimed as new and desired to be secured by Letters Patent of the United States, is:—

1. A sash lock comprising a casing, having a reciprocating bolt, said bolt provided with a ratcheted face on one side and a rack upon another side thereof, a spring actuated bolt retaining device movably mounted between the bolt and its casing to engage said ratcheted face and a cylindrical fulcrum positioned upon a wall of the casing to be engaged by said bolt retaining device.

2. A sash lock comprising a reciprocating bolt provided with a rack, and a ratcheted face, a key operated pinion adapted to en-

gage said rack to reciprocate the bolt when said pinion is engaged by its key, a spring actuated bolt retaining device to engage said ratcheted face to retain the bolt in a plurality of predetermined positions, and a key to release said retaining device and to reciprocate said bolt.

3. A sash lock comprising a reciprocating bolt provided with a rack and a ratcheted face, a key actuated pinion to engage said rack, a spring actuated bolt retaining device positioned beside said bolt to engage said ratcheted face, a cylindrical fulcrum to provide rocking engagement for said bolt retaining device, a pintle piercing said bolt retaining device at its forward end to retain said bolt retaining device in locking engagement with said cylindrical fulcrum, one end of said pintle slidably engaging a recess in the lock casing, and a key to actuate said bolt retaining device by engaging the other end of the pintle.

4. A sash lock comprising a casing having a removable wall provided with an aperture, a reciprocating bolt carried by said casing and provided with a ratcheted face and a rack face, spring actuated means to engage the ratcheted face to maintain the bolt in a predetermined position, said spring actuated means having a pintle which is adapted to be positioned adjacent the rack, a pinion rotatably mounted in the aperture in the removable wall of the casing and adapted to journal upon the pintle to engage the rack of said bolt and means to rotate the pinion.

5. A sash lock comprising a casing having a removable wall provided with an aperture, a reciprocating bolt mounted in the casing and provided with a rack, means carried by the casing provided with a pintle, a pinion rotatably mounted in the aperture of the removable wall of the casing and also rotatably mounted on said pintle for removal with the casing wall and removable means to rotate said pinion to reciprocate said bolt.

In testimony whereof, I affix my signature, in presence of two witnesses.

FRED E. SPARKS.
